UNITED STATES PATENT OFFICE.

HENRY W. HOLLY AND ALBA F. SMITH, OF NORWICH, CONNECTICUT. AS-SIGNORS TO ALBA F. SMITH.

IMPROVED ROLLER FOR WRINGING-MACHINES.

Specification forming part of Letters Patent No. 39,201, dated July 7, 1863.

To all whom it may concern:

Be it known that we, HENRY W. HOLLY and ALBA F. SMITH, of Norwich, in the county of New London and State of Connecticut, have invented certain new and useful Improvements in the Construction of Rolls for Clothes-Wringing Machines and other Purposes; and we do hereby declare that the following is a full and exact description thereof, which is prepared with a view to the issue of Letters Patent therefor.

The accompanying drawings form a part of this specification.

Figure 1 is a side view of the roller detached from the machine. Fig. 2 is a longitudinal central section. Fig. 3 is a cross section on the line S S in Figs. 1 and 2. Fig. 4 is a cross-section on the line T T in Figs. 1 and 2. Fig. 5 is an end view, and Fig. 6 is a side view, of the exterior end plate or wheel. Fig. 7 is an inside view of the same, or a view of the face which is presented against the roll. Fig. 8 is a view of the exterior face of the inner or first end plate. This plate is applied before and underlies the plate shown in Figs. 5, 6, and 7. Fig. 9 is a side view of the same. Fig. 10 is a side view of plates or wheels introduced between the disks of elastic material throughout the entire length of the roll.

Similar letters of reference indicate like parts in all the figures.

Our invention is exhibited in its most complete form in the drawings. The single roll here represented is composed of cork covered with a layer of cloth and supported by a rigid core of metal, but the material of all the parts may be varied at will.

To enable others properly skilled to make and use our invention, we will proceed to describe its construction and operation by the aid of the drawings and of the letters marked thereon.

A is a shaft which we prefer to make of iron galvanized, and A' is a spline or ridge extending along the entire working part of the roll. We prefer to make this by soldering a wire upon the surface of A, or letting it partly into A and then soldering it, but we can accomplish our purpose by making a square shaft with corresponding holes in B B B.

B B B, &c., are castings adapted to slip endwise along the shaft A A' but so fitted

that each is restrained from turning around thereon. Each piece B is armed on each side at its periphery with a flange, b b'. This may be roughened or toothed, or otherwise made irregular, in order the better to fulfill their function of holding firmly the elastic material, but we have found them very successful even when entirely plain and quite smooth, as represented.

C C O, &c., are rings or disks of cork which are introduced by slipping them on from the end of the shaft, one being introduced, after each piece B b, so that the rings C and castings B b alternate, as represented. On these parts being forcibly compressed and held together the cork is indented and compressed at the points b b more than it is at points nearer the shaft, and is condensed more at all these points than at and near the periphery of the roll. This causes the cork to be grasped and held very firmly at and near its center, while its exterior is but slightly condensed and is ready to act with its full measure of elasticity in yielding to inequalities in the clothes.

Rubber and other elastic or compressible material may be used in place of cork for the rings C; but we have found cork to be cheaper and more durable.

We cover our roll and secure the ends by means now to be described.

D D' are plates, or, rather, open wheels of galvanized iron of the form represented; and H H' are pins which extend through holes H H' in the shaft A in the manner represented. These pins H H' secure the wheels D D', and also the additional rings or plates E E', and by confining those in the relations represented they secure the enveloping-cloth G. To apply these parts properly, we first compress the mass of material B C to the proper extent by the aid of suitable machinery (not represented) acting in the line of the axis, and insert in the holes H H' short temporary pins. (Not represented.) We then compress the entire periphery of the roll radially by inclosing it in a hollow cylinder of less diameter than itself. We afterward force the entire roll endwise out therefrom, applying the cloth tube G properly to one end before the movement commences and fitting it to each part successively as it escapes. These operations are best conducted after the cork or other

elastic material C has been reduced by the application of moisture or heat, or both, to its most yielding condition, and the same is true of the operations for securing the ends. These latter consist in first folding the ends of the cloth or other enveloping material G over upon the ends of the roll, laying the folds properly disposed upon the outer face of the wheels D D'; next applying the rings E E' in such position that the points e e' coincide with the open spaces in the wheels D D'; next pressing together these rings E E' with such force as to drive the points e e' through the spaces in D D' into the cork; and by thereby carrying the folded part of the cloth through the holes in D into the cork it draws it endwise toward each end of the roll and causes it to fit very tightly. We, lastly, drive out the short temporary pins referred to above and substitute longer pins, H H', which are allowed to remain, being each embedded or partially embedded in a corresponding cross-groove on both D and E, so that it prevents their turning as well as prevents the end movement. On releasing the roll from its confinement it will now be found completely and tightly enveloped by the cloth G and by the several end pieces, and with its elastic disks in such condition that while very tightly compressed and firmly held near its center it is very open-grained and elastic at its periphery.

We do not confine ourselves to the materials described, and may, when the price will warrant it, make a better roll by using brass instead of galvanized iron for A B, &c., and rubber-cloth or rubber alone, or any other suitable material instead of cloth, for the envelope G. The roll represented is not provided with a crank, but is adapted to be the driven rather than the driving roll of a machine. We prefer thus to use our roll when we use but one in a machine; but our invention is suitable to be applied to both rolls of all clothes-wringing machines, and to a great variety of machines used in manufacturing establishments, &c., power being applied through their shafts, or not, as may be preferred.

Some of the advantages due to certain features of our invention may be separately enumerated as follows:

First. By the use of hard rings between the disks of elastic material C and the so holding of these rings that they are free to slide endwise, but not to rotate around upon the shaft A, we compress and take hold of each disk C, not alone with the force due to its radial strain or simply its compression upon and adhesion to the shaft, but also by an end force or a force acting in lines parallel to the axis, which may be increased indefinitely without in any sensible degree affecting the elasticity of the surface of the roll; and the torsional strain or the tendency of the roll to turn around upon the shaft is transmitted from each disk C directly to the shaft, and is there met by the spline A' or an equivalent provis-

ion for the purpose. This feature of our invention provides, in fact, a complete endwise hold of each disk—not a hold of each disk upon the adjacent disks, but of each directly upon the shaft itself.

Second. By the employment of the flanges b b' at or near the periphery of the castings B, so as to make the rings practically thicker there than nearer the axis, and compelling the elastic material to assume the opposite form at the corresponding points, and to ultimately become "set" in this condition, we practically dovetail the elastic rings C to their places between the rings B so effectually that even if a ring, C, should entirely split or should divide into a number of independent parts, which it is not likely to do, the parts would be held not by a simple grasping, as in a vice, but by an actual locking of the parts together in the manner of a "lewis."

Third. By the employment of our covering G, tightly fitted upon the exterior of the disks C, of elastic material in the manner represented, we are able to use a poorer quality of rubber, cork, &c., or to compose the disks of a material less adapted in its nature to serve the purpose intended by reason of its being more liable to crack and fracture. The disks are also compelled to act as a unit, and not to be each compressed independently, for the covering G not only protects but also unites the disks, and by reason of the transmission of the strain applied at any one point through the presence of the covering G to all the points adjacent thereto we avoid the liability of one disk becoming much more compressed by the presence of a button or the like than its neighbors. Without the covering G one disk might be condensed and slip inward between its neighbors and be held there by the friction. The covering G, on the contrary, compels the surface of its neighbors to accompany it and the elasticity of its neighbors to contribute to avoid any such disarrangement of the surfaces.

Fourth. By the use of our two disks or wheels D and E, with the points or spurs e and pin H arranged as represented, we draw the cloth very tightly and conveniently, and secure the ends of the entire mass of soft material with a single pin and with little expenditure either in labor or material.

Having now fully described our invention, what we claim as new therein, and desire to secure by Letters Patent, is—

1. In the construction of soft and elastic rolls the employment of soft pieces C C, hard pieces B B, and the splined or equivalent shaft A A', arranged to operate together in the manner and for the purpose herein set forth.

2. In connection with the yielding pieces or disks C C and hard pieces B, arranged as specified, the employment of the projections b b', or either of them, arranged substantially as and for the purpose herein set forth.

3. The combination of the tightly-fitted

covering G with disks of soft material C, and suitable means of confining the same, substantially as and for the purpose set forth.

4. The spurred plates or wheels at one or both ends of the roll, as represented by E e, arranged as represented relatively to the open plate D, covering G, and pin H, or their re-

spective equivalents, for the purpose herein set forth.

HENRY W. HOLLY.
